UNITED STATES PATENT OFFICE.

VIRGINIA W. COLLIER, OF BLOOMFIELD HILLS, MICHIGAN.

PORTABLE DRESSING-CABINET.

1,288,518.

Specification of Letters Patent. Patented Dec. 24, 1918.

Application filed July 5, 1918. Serial No. 243,333.

To all whom it may concern:

Be it known that I, VIRGINIA W. COLLIER, a citizen of the United States of America, residing at Bloomfield Hills, in the county of Oakland and State of Michigan, have invented certain new and useful Improvements in Portable Dressing-Cabinets, of which the following is a specification, reference being had therein to the accompanying drawings.

It is the object of the invention to obtain a light and compact portable dressing cabinet which may be easily carried from place to place being more particularly designed for use by bathers. To this end the invention comprises the novel construction as herein after set forth.

In the drawings:

Figure 1 is a perspective view of the cabinet set up in condition for use;

Fig. 2 is a horizontal section;

Fig. 3 is a plan view of the structure collapsed ready for folding;

Fig. 4 is a perspective view of the case in which the structure is stored and carried;

Fig. 5 is a perspective view showing the jointed supporting posts or rods;

Fig. 6 is a section division showing the manner of joining the post sections; and

Fig. 7 is a vertical section, showing the manner of securing the top section and braces.

My improved structure comprises essentially a light fabric forming the walls, top and floor of the structure, together with posts formed in jointed sections. The length of the post sections is such as to permit of storage in a small space and the fabric walls, top and floor are capable of being folded and rolled, so that the entire structure may be placed in a comparatively small case.

In detail, A are the posts each of which is shown as formed in two sections detachably jointed to each other by suitable means such as a sliding sleeve B. The lower sections of the posts may be provided with pointed ends C for driving into the ground to secure the structure in place. D, D', D² and D³ are the fabric side sections, E is the cover section and F the floor section. As shown all of these sections are united to each other and are also secured to the posts A, as indicated in Fig. 3. This will permit of folding and rolling by first unjointing the post sections, then folding along the

longitudinal line G—G, then folding in the cover and floor sections E and F and then rolling the folded fabric. The post sections will be rolled in with the fabric and the length is so diminished that a comparatively short case H will be capable of receiving the package. This case may be provided with a handle I for convenience in carrying.

To set up the cabinet the fabric is unfolded and the post sections are joined by the sliding of the sleeves B over the abutting ends. The floor section F is preferably provided with eyelets J for slipping over the lower pointed ends of the posts and the cover section E is secured over the ends of the posts by any suitable means, such as eyelets J' engaging upwardly extending pintles J². The top section is also preferably provided with projecting flaps L which will overlap the upper edges of the side section D—D', etc., and will conceal the joint. These flaps may also be secured by snap fasteners K to the sides of the posts. One of the side sections, such as D, forms the door and may be secured preferably to the inside of one of the posts, as indicated at M, either by a snap-fastener, turn-button or other suitable securing device. To hold the posts in spaced relation from each other braces, such as N, may be used, and as shown these are adapted to engage with the pintles J² at the upper ends of the posts. These braces are preferably permanently attached to the top section E, as by means of the eyelets J and can be turned into parallelism when the fabric is to be folded, as shown in Fig. 3, or to extend at right angles to each other when in engagement with the pintles, as shown in Figs. 2 and 7.

In use, when the cabinet is set up the user may enter through the open side, which is then closed by the section D and securing devices M. As these securing devices can be manipulated only from the inside they form a lock for the door when the cabinet is occupied. To collapse the cabinet the top section is disengaged, the braces folded, the posts withdrawn from the ground and disjoined, after which the fabric may be folded as previously described.

It will be appreciated that a structure formed as described may be manufactured at small cost and may be conveniently carried from place to place. The work of set-

ting up and taking down is quickly performed without requiring skill on the part of the user.

What I claim as my invention, is:

- 5 1. A portable dressing cabinet comprising fabric side, top and floor sections united to each other, posts formed in jointed sections united to said fabric sections permitting when unjointed of folding and rolling the fabric with the post sections rolled therein, and folding braces for engaging the upper ends of said posts to hold the same in spaced relation.
- 10 2. A portable dressing cabinet comprising fabric side, top and floor sections, posts formed in jointed sections and adapted when unjointed to be rolled in with the folded fabric, eyelets on said top and floor sections for engaging said posts, and folding braces for engaging the upper ends of said posts to hold the same in spaced relation.
- 15 3. A portable dressing cabinet comprising

ing permanently connected fabric sides and a top and a bottom permanently connected respectively to the upper and lower edges of 25 one of said sides, and posts secured respectively at the junctures of said sides and at one of the two free edges thereof, means for securing the other free edge to the last-named post, and means for securing the top 30 and bottom members to the upper and lower extremities of the posts.

4. A portable dressing cabinet comprising fabric side, top and floor sections and jointed posts supporting the side and top, and 35 adapted when unjointed to be rolled in with the folded fabric, means for engaging the top and floor sections with said posts and folding braces for engaging the upper ends 40 of said posts to hold the same in spaced relation.

In testimony whereof I affix my signature.

VIRGINIA W. COLLIER.
